MASKING UNIT FACE FOR BOWLING ALLEYS

Elwood D. Jarrett, Salina, Kans., assignor to Jarrett Electric, Inc., Salina, Kans., a corporation of Kansas

Filed Aug. 12, 1960, Ser. No. 61,729

Term of patent 7 years

(Cl. D34—5)

Fig. 1.

Fig. 2.

Fig. 3.

Fig. 1 is a front elevation of a masking unit face for bowling alleys embodying my new design.

Fig. 2 is a side elevation thereof.

Fig. 3 is a plan view thereof.

I claim:

The ornamental design for a masking unit face for bowling alleys, as shown.
